(57) CLAIM

The ornamental design for a spoon lure for fishing, as shown and described.

DESCRIPTION

FIG. 1 is a perspective view of a first embodiment of the spoon lure for fishing;

FIG. 2 is a top plan view thereof;

FIG. 3 is a bottom plan view thereof;

FIG. 4 is a left side view, with the right side view being a mirror image thereof;

FIG. 5 is a front view thereof;

FIG. 6 is a rear view thereof;

FIG. 7 is a perspective view of a second embodiment of the spoon lure for fishing;

FIG. 8 is a top plan view thereof;

FIG. 9 is a bottom plan view thereof;

FIG. 10 is a left side view, with the right side view being a mirror image thereof;

FIG. 11 is a front view thereof; and,

FIG. 12 is a rear view thereof.

The broken lines depict environmental structure that are for illustrative purposes only and form no part of the claimed design.

1 Claim, 6 Drawing Sheets
